(57) CLAIM

The ornamental design for the light pod, as shown and described.

DESCRIPTION

FIG. 1 is a top/front-perspective view of the light pod.

FIG. 2 is a top/rear-perspective view of the light pod.

FIG. 3 is a bottom/front perspective view of the light pod.

FIG. 4 is a front view of the light pod.

FIG. 5 is a rear view of the light pod.

FIG. 6 is a bottom view of the light pod.

FIG. 7 is a top view of the light pod.

FIG. 8 is a right-side view of the light pod; and,

FIG. 9 is a left-side view of the light pod.

In these drawings, the solid lines illustrate the claimed ornamental design, whereas the broken lines illustrate environmental features that form no part of the claimed ornamental design.
